DESIGN FOR A VACUUM TUBE

William W. Eitel, San Bruno, and Jack A. McCullough, Millbrae, Calif., assignors to Eitel-McCullough, Inc., San Bruno, Calif., a corporation of California

Application July 13, 1942, Serial No. 107,512

Term of patent 14 years

To all whom it may concern:

Be it known that we, William W. Eitel and Jack A. McCullough, citizens of the United States of America and residents, respectively, of San Bruno and Millbrae, county of San Mateo, State of California, have invented a new, original, and ornamental Design for a Vacuum Tube, of which the following is a specification, reference being had to the accompanying drawing, forming part thereof.

Referring to the drawing:

The figure is a perspective view of a vacuum tube, showing our new design.

The characterizing features of our design for the vacuum tube shown reside in the specific dome-shaped plate cap and conical supporting member rising therefrom and converging into the vertically disposed plate lead wire, all as illustrated.

We claim:

The ornamental design for a vacuum tube, substantially as shown and described.

WILLIAM W. EITEL.
JACK A. McCULLOUGH.
